G. Colhoun,

Car Ventilator,

No 26,967

Patented Jan. 31, 1860.

Inventor

George Colhoun

UNITED STATES PATENT OFFICE.

GEORGE COLHOUN, OF PHILADELPHIA, PENNSYLVANIA.

VENTILATOR.

Specification of Letters Patent No. 26,967, dated January 31, 1860.

To all whom it may concern:

Be it known that I, GEORGE COLHOUN, of Philadelphia, in the county of Philadelphia and State of Pennsylvania, have invented a 5 new and useful Improvement in Ventilators for Railroad-Cars, &c.; and I do hereby declare that the following is a full, clear, and exact description of the same, reference being had to the accompanying drawings, 10 forming a part of this specification, in which—

Figure 1, is a vertical longitudinal section of a car with my improvement applied to it. Fig. 2, is a front view of the same.

15 Similar letters of reference, in each of the several figures indicate corresponding parts.

Before stating my invention I will premise by saying that I am aware that cones 20 have been used on top of a car for the purpose of ventilation, and that therefore I do not intend to cover any new principle by my patent.

The nature of my invention consists in 25 the inner and outer receiving cones C, D, elbow pipe B, and flaring discharge pipe F, when the whole is constructed, arranged and combined in the manner hereinafter described.

30 The essential peculiarity of my invention lies in the arrangement of the outer cone so that its rear end extends to or beyond the discharge end of the elbow pipe, and its forward end a considerable distance forward of both the vertical part of the elbow and the mouth of the inner cone. And it is 35 this peculiarity, in connection with the flaring discharge pipe, inner cone and elbow pipe that, as I have found by experiment, 40 renders this character of ventilator useful and effective to the extent required. With my arrangement, an annular current of air in a concentrated or compacted state is conveyed to the discharge end of the elbow pipe 45 and then discharged and expanded suddenly into the flaring discharge pipe. And at the same instant a solid current of air concentrated or compacted, is discharged through the elbow pipe and thus while a

50 powerful suction is produced up through the elbow pipe by the annular current, the effect of said current is accelerated by this central solid current and consequently a per-

fect withdrawal of the vitiated air from the car insured, and room thus provided for 55 pure fresh air to rush into the car through the crevices or doors and windows. By this combination and arrangement, the air, as the car moves along, is compressed or compacted all around the outside of the 60 elevated elbow pipe and also within the inner cone, and then suddenly escapes through and outside of the mouth of the elbow pipe in such a manner as to produce a vacuum in the elbow pipe and a consequent rushing 65 out of the vitiated air which the car contains. As soon as the vitiated air is removed, its place is supplied with fresh air through crevices, or the doors and windows.

To enable others, skilled in the art, to 70 make and use my invention, I will proceed to describe its construction and operation.

A, represents a rail-road car.

B, is the elevated elbow pipe. It is let into the top of car so as to be capable of 75 being revolved.

C, is a hollow truncated cone with its truncated end inserted into the rear of the elbow pipe at a point just in line with the discharge of the horizontal portion of said 80 pipe. The truncated end of this cone may, if desired, have a flaring mouth put on it, as illustrated by dotted lines so as to extend to near the discharge end of the elbow pipe.

D, is the main outer cone, it incloses the 85 cone C, and a greater portion of the elbow pipe, as represented. Its truncated end meets, about at the termination of the horizontal portion of the elbow pipe, a flaring discharge or mouth piece, E, as represented. 90

From this description, it will be evident that as the car moves forward, a powerful suction will be produced up through the pipe by means of the inner and outer cones, and the vitiated air will be exhausted from 95 the car and thus room provided for the entrance of pure fresh air through the door and windows or crevices.

The pipe being set so as to revolve as usual, the ventilator answers both in going 100 and returning with the train. With a very little change in the manner of applying my combination and arrangement and providing it with a weather vane, it will answer a most excellent purpose for all places where 105 ventilation or strong draft is required.

What I claim as my invention and desire to secure by Letters Patent, is—

The inner and outer receiving cones C, D, elbow pipe B, and flaring discharge pipe F, 5 when the whole is constructed, arranged and combined, substantially as and for the purpose set forth.

The above specification of my improvement in ventilators signed by me this 15th day of November 1859.

GEORGE COLHOUN.
